UNITED STATES PATENT OFFICE.

EUGENE K. McLAIN, OF WEBSTER CITY, IOWA.

SPRING WHEEL.

Application filed May 14, 1920. Serial No. 381,376.

To all whom it may concern:

Be it known that I, EUGENE K. McLAIN, a citizen of the United States, residing at Webster City, in the county of Hamilton 5 and State of Iowa, have invented new and useful Improvements in Spring Wheels, of which the following is a specification.

This invention has reference to vehicle wheels.

10 An object of the invention is to produce a spring wheel for vehicles which will have all of the advantages of a pneumatic wheel, and which in addition thereto will engage the ground in a better manner so that skidding will be positively prevented.

A further object of the invention is to construct a resilient wheel in which the spokes are in the nature of arched springs, of a particular construction which reinforces and 20 strengthens the same, said springs having their outer ends pivoted to shoe housings which latter are connected together by pivoted links, while in the housings are shoe blocks of reinforced compressible material 25 which are removable and replaceable in ease of wear, and which are of a construction to have their engaging surfaces contact with the ground for the entire area of said surfaces.

30 Other objects and advantages will present themselves as the nature of the invention is better understood, reference being had to the accompanying drawings.

In the drawings:—

35 Figure 1 is a side elevation of a vehicle wheel constructed in accordance with this invention.

Figure 2 is a detail vertical longitudinal sectional view through one of the shoes 40 showing the spring spoke connected therewith and also illustrating the links which connect the shoe to the adjacent shoes.

Figure 3 is a section view approximately on the line 3—3 of Figure 1.

45 Figure 4 is an enlarged side elevation of two of the shoes in ground contacting position, parts being broken away and parts being in section.

Figure 5 is a perspective view of one of 50 the spokes employed.

Figure 6 is a perspective view of one of the shoe housings.

Figure 7 is a similar view of one of the 55 shoes.

Figure 8 is a transverse sectional view approximately on the line 8—8 of Figure 2.

In the showing of the drawings, the hub 10 is provided with stub spokes 10' to which are secured the inner ends of spring spokes 11. 60

Each spoke is constructed of arched spring metal and each of said spokes includes a main member 12 and an auxiliary member 13. The main members of the spokes are connected to the shoe carrying 65 housings, as will be hereinafter more fully set forth, while the auxiliary members are of a less length than the main members, being connected with the main members to the hub, but being of a length slightly greater 70 than one-half the length of the main members. The main and auxiliary members are arranged inlapping relation, and each of the auxiliary members has its outer end, at 75 the corners thereof, formed with ears 14 which are bent over the main members 12.

The outer ends of the spokes 11 are rounded upon themselves to provide sleeves 16. The shoes, which constitute the tread portion of the wheel are each mounted in a 80 metallic member that is in the nature of a housing, and the said housings are indicated by the numeral 17. Each housing is of a substantially rectangular formation, having its inner periphery, at its sides, provided 85 with ears 18. Passing through the ears are bolts 19, and these bolts also pass through the sleeves 16 of the respective spokes 11. The bolts are engaged by nuts 20, whereby the housings and spokes are removably connected. 90

Inward with respect to the bolts 19, and to one side thereof, there is passed through the ears of each of the housings an additional bolt 21. On each of the last mentioned bolts there is a revoluble sleeve 22, and each of the bolts is engaged by a nut 23. 95

The ends of the housings at the corners thereof are provided with outstanding extensions which may be termed ears and 100 which are designated by the numeral 24. Through these ears pass bolts 25 engaged by nuts 26. The bolts also pass through suitable openings in the ends of links 27, and it is through the medium of these links that 105 the housings 17 are connected together.

In each of the housings 17 there is a shoe which is in the nature of a substantially rectangular body. These shoes, broadly indicated by the numeral 28, are removably 110 secured to the housings through the medium of bolts 29 that pass transversely through

the housings and through the portions of the shoes received in the housings, and the said bolts are engaged by nuts 30.

Each of the shoes comprises an outer 5 traction block 31 on which is formed a reduced rectangular portion 32 of a size to be snugly received in the housing 17. The traction surface or portion of each of the shoes is of compressible material, being preferably in the nature of vulcanized rubber. The different materials constituting the shoes are held together by bolts 33 that pass therethrough. The traction portions of the shoes are reamed so that the heads of the 15 bolts may be received therein, and thereafter the reamed portion is plugged as indicated by the numeral 34.

The threaded ends of the bolts are received in sockets 36 in the inner face of the 20 portion 32 of the shoes whereby nuts 35 may be screwed on the said bolts. In this manner a worn shoe may be repaired, and as the shoes are removably connected with the housings, a worn shoe may be readily removed 25 from the wheel without necessitating the removal of the other shoes.

Portions of at least two shoes 31 of the wheel are at all times in ground contacting 30 position. It is to be noted that the members 16 and 21 are pivotally supported to one side of each other. Naturally the lower spokes of the wheel are under greater compression than the upper spokes, and while the said spokes have been described as 35 arched, they are retained at a curvature through the medium of the link connection between the housings of the shoes, and have a natural tendency to resume normal position. The spring spokes under compression 40 naturally assume a position away from the roller 22. Now just after one of the shoes leaves the ground, the spring spoke connected therewith, having a tendency to straighten itself will move to contact with the roller 22 on the bolt 21 and will 45 naturally swing the end of the housing connected by the link 27 with the housing of the shoe next to ground leaving position. The result is that the first mentioned

shoe will be canted or tilted so that its end 50 nearest the ground engaging shoe will be swung downwardly, such action being permitted by the link connection between the housings, and such downward swinging of the shoe will naturally cause one corner 55 thereof to contact with the ground to effect a kicking action against the ground, and therefore give an added impulse to the wheel in the turning thereof.

Having thus described the invention, what 60 I claim is:—

1. In a vehicle wheel, a hub having arched spring spokes radiating therefrom and all of said spokes being arched in the same direction, a rim made up of spaced members 65 each carrying a compressible shoe and each having a loose connection with each other, means pivotally connecting the spokes to the respective rim section, means in the path of engagement with the spokes, designed to 70 be contacted by each spoke in the expansion thereof when the same is brought out of ground contacting engagement to tilt the rim section pivoted to the spoke to cause the same to exert a kicking action against 75 the ground surface.

2. In a wheel, a hub, spring spokes arched in the same direction radiating from the hub and decreasing in resiliency from the inner to the outer ends thereof, a rim made 80 up of sections, and each spoke being pivotally connected to one of the rim sections, a loose connection between the respective rim sections, a tread block carried by each rim section, and revoluble means on each rim 85 section disposed to one side of the pivotal connection of the springs with said rim section and normally in the path of contact with but out of such contact with the spokes for the shoes in ground contacting position 90 designed to be successively contacted by said spokes as the shoes thereof leave the ground whereby to tilt the rim sections to cause the tread blocks thereon to exert a kicking action against the ground surface in the turning of the wheel. 95

In testimony whereof I affix my signature.
EUGENE K. McLAIN.
